Application July 30, 1936, Serial No. 93,329

4 Claims. (Cl. 101—420)

This invention relates to improved printing means.

This application is a continuation in part of my allowed co-pending application Ser. #616,414, filed June 10th, 1932, entitled Improved printing means.

More particularly, my invention is directed to coating a web of printed paper or other suitable material with a layer of varnish or equivalent agent, preferably regulated in its applied thickness, whereby the web may be re-wound, or cut and staked, or otherwise handled, substantially immediately after printing and/or other impressions, to thereby preclude offsetting upon a contacting surface of the impression while wet, the application of the coating being had in the form of a substantially continuous film of liquid by means free of contact with the printed material and the printing or impressions thereon and in a manner without loss of ink and design value.

My invention also applies to suitable apparatus for carrying out my process.

My invention is applicable for similarly coating individual printed sheets to prevent offsetting when stacked.

My invention, in addition to precluding offsetting, may, if desired, bring about an enhanced effect upon the printed matter in that the coating agent serves to impart a sheen or brilliancy, and otherwise contribute definitely in artistic effect upon the resulting product.

My invention is particularly applicable for multicolor printing, the colored printed impressions being applied in advance of the application of the offset-preventing agent.

Supplemental to the aforesaid improvements, my invention is particularly advantageous in deriving impressions of gold, silver, aluminum and other metallic "colors", either in genuine or imitation metals, alloys, or the like, in which instances of use the offset-preventing coating agent serves as a bonding medium for the one or more metallic "colors."

Further features and objects of the invention will be more fully understood from the following detail description and the accompanying drawings, in which

Fig. 1 illustrates in side elevation, largely in diagrammatic form, of printing in a plurality of colors, two being indicated, upon a web of paper and the step of applying a film of offset-preventing material. This view also indicates the step of re-winding of the printed web;

Fig. 2 is a side elevation, on an enlarged scale, of roller parts of any approved type of mecha-

nism for applying varnish lacquer or equivalent offset-preventing material;

Fig. 3 is a side elevation, on an enlarged scale, of roller parts of a web-advancing mechanism;

Fig. 4 illustrates in side elevation, largely in diagrammatic form, the printing in two colors, the step of applying varnish or equivalent offset-preventing material and the further step of impressing a metallic "color";

Fig. 5 is a diagram in side elevation illustrating the application of my invention to printing the opposite, that is, the reverse faces of a web of paper and to preclude offsetting;

Fig. 6 is a side elevation, on an enlarged scale, of a preferred form of unit for applying an offset-preventing medium;

Fig. 7 is a detail elevation, also illustrating certain parts in different operated positions, taken on line 7—7 of Fig. 8;

Fig. 8 is a front elevation of Fig. 6, (the portions of the parts between the planes of the indicated dash lines being omitted for the purpose of saving space for illustration);

Fig. 9 is a sectional elevation, on a further enlarged scale, on line 9—9 of Fig. 8; and

Fig. 10 is a modification of Fig. 3.

In general, the invention relates to the application of a suitable agent in film or other regulated layer, preferably co-extensive with the area of the printed surface, applied directly onto the still-wet ink or other impression media, for preventing offsetting of the printed matter.

My invention is particularly applicable, but not limited to the printing of paper or equivalent material in web form in a plurality of colors, the color impressions being conveniently applied in any suitable type of accepted or other approved multi-color printing machine, such as the Chambon printing machine, indicated in the accompanying drawings, whereby the respective colors are applied successively to the web. Accordingly, the representations in the accompanying drawings depicting the Chambon type of printing machine are for illustrative purposes only and represent but one preferred form of carrying out my invention.

Referring to the diagrammatic showing in Fig. 1, a roll 10 of paper web may be rotatably supported in any suitable manner, as by means of the oppositely disposed bracket arms 11, each having a forked bearing 12 for freely receiving a rod or other supporting shaft 13, passing through the central core of the roll 10. The free end 14 of the web may pass about a set of guide rollers 15, thence between a pair of pressure pull

- rollers 16; the web 14 may thence continue in a substantially horizontal direction, as indicated by the applied arrows, to the first printing unit 17, then to the second printing unit 18, et cetera, 5 for the desired number of colors to be impressed. Each printing unit may be of conventional construction, and comprises essentially a printing roll 19 and an impression roll 20; the printing roll 19 is illustrated as disposed above its 10 associated impression roll 20, in which arrangement the printing is effected on the upper face of the web 14.
- The above stated printing units are preferably mounted on a common support, such as a table 21. 15 The table 21 is preferably mounted on a base 22, arranged for adjustably setting the upper face of the table 21 in a substantially horizontal level.
- It will be understood that each printing unit 20 equipment includes suitable inking rollers, an ink font, and the usual appurtenant devices, inclusive of roller adjustment for the printing and impression rollers, all as well known to those skilled in the art.
- 25 In carrying out the more simple embodiments of my invention, the web 14, after impression of the desired printing and/or metalizing is treated with a film or other regulated layer of the offset-preventing agent, as for example, a varnish, lacquer, or other suitable medium, such as may be prepared by dissolving cellulose, gums or resins, such as Manilla copal, shellac, rosin, or any other suitable natural or synthetic resin, in a solvent or solvents suitable for such solution, 30 and whose rate of evaporation is adjusted to the requirements of the process.
- The application of the film or layer of the agent is preferably made without physical contact of the mechanism applying the agent, the 35 solution or emulsion of the agent being applied under regulated conditions from its supply onto the printed face of the web, as will appear more fully hereinafter.
- As one form of such agent applying mechanism, I have illustrated the unit 23, which may be and preferably is mounted on the upper face of the table 21.
- The unit 23 comprises essentially an agent-supplying roller 24, which, in this instance, is 40 shown disposed above the upper, that is, printed face of the web 14; the unit 23 also includes a roller 25 for supporting the opposite, that is, lower face of the web, in regulated relation with respect to the agent supplying roller 24. A receptacle 26 containing the supply of the agent, is suitably arranged with respect to the supplying roller 24, to apply a continuous regulated film or coating of the agent upon the roller 24.
- Referring to Fig. 2, the upper roller 24 is 45 shown engaging the edge portion 14a of the web 14, the width of the printed area being indicated by the lines 14b. In such embodiment, the outermost, opposite flanges 26, 27 of the roller 24 are substantially equal, the inner diameter 28 being of slightly reduced dimension as 50 compared with that of its associated outer flange 26, the difference in radial dimension being substantially that of the thickness of the web 14.
- Such arrangement thereby provides for the 55 clearance 29 between the surface of the printed area 14b on the web 14 and the cylindrical surface of the reduced portion 24c of the roller 24, the dimension of the clearance 29 for a given thickness of web being regulated by the diameter dimension of the cylindrical portion 24a

relative to the diameter dimension of the outer flange portions 26, 27, whereby the film or layer of the offset-preventing agent is regulated in thickness of application.

The arrangement of the set of rollers 30, 31, 5 see Figs. 1 and 3, shown positioned posteriorly of the offset-preventing agent applying mechanism, above described, is typical of rollers for advancing the web. As illustrated, the enlarged flange 32 of the roller 31 engages the edge portion 14a of the web 14. The enlarged diameter of the flange 32 relative to that of the body portion 30a of the roller 30 provides for clearance between the cylindrical periphery of the body portion 30a from the layer or film 14e of the 10 offset-preventing agent applied to the printed area 14b of the web.

The dryer 33 is of any suitable construction; the atmosphere within the dryer is regulated in temperature by suitable means, such as an electrical 20 heating unit, or by steam coils or equivalent means, indicated schematically at 34, or by the use of heated air; under certain conditions, cooling is advantageous.

The web 14 upon completion of the printing 25 and the application and drying of the offset-preventing agent may be re-wound, as indicated at 35.

The above indicated web-pulling rolls 16, the sets of rolls of the printing units, the offset-preventing agent applying means, the pull rollers 30, 31, and any other supplemental sets of rolls are preferably positively driven in substantial synchronism, as by means of an electric motor 36, 30 driven as by a belt 37, to the driving shaft 38 35 suitably rotatively mounted and extending along the table 21 and positively connected by spiral and/or other gears with the shafts of the respective sets of rolls.

If desired, the web 14, after completion of the 40 stated operations, may be slit longitudinally of the web, and the respective slit lengths re-wound individually, or cut transversely into individual printed sheets, and stacked.

The length of the dryer 33 and its temperature 45 are regulated pursuant to the rate of travel of the web, to effect substantially complete drying of the offset preventing material when it is desired to re-wind the web, or to slit and cut and stack the individual printed sheets.

When it is desired to apply a metallized impression, see Fig. 4, such operation is carried out at the conclusion of the desired multi-color printing and after the application of the offset-preventing agent, as hereinabove set forth, relative 55 to Fig. 1, like parts being designated by like reference numbers; however, in the instance of metalizing, the dryer 33a effects a lesser drying action, as by a lower temperature provided by the heating means 34, or of less effective length of the 60 dryer 33a, whereby the offset-preventing agent is still tacky when the web 14 attains the metalizing applying unit 40.

The metalizing impression unit 40 may be of 65 any suitable type by which finely divided or metal leaf is applied.

Upon completion of the metalizing impression, the web 14 is passed through the drying device 41 for final drying of the metallized imprint and 70 the offset-preventing film or layer. The web 14 is continued in its transit past the set of rollers 30, 31, either to be re-wound or slit and cut into individual printed sheets.

If desired, the metalizing medium may be ap- 75

plied in advance of the application of the protecting coating.

Fig. 5 illustrates a manner of transit of the web 14 for applying printed matter protected by a 5 film or layer of offset-preventing medium to the inverse face of the web, whereby both faces of the web bear printed matter which is proofed against offsetting.

Referring to Fig. 5, the web 14 is passed through 10 the set of feed rolls 45, guide rolls 46, 47, 48, to the one or more printing units 58, for printing on one face of the web, thence through the offset-preventing agent applying unit 23, oven 33a and supplemental cooling unit 33b, thence through 15 the plurality of printing units 51, 51, for printing on the opposite face of the web, thence through the offset-preventing agent applying unit 23, and final dryer 33, whereafter the web is rewound or slit and cut into individual sheets.

20 In Figs. 6 and 9 is illustrated a preferred form of agent applying unit. Such preferred form embodies the feature of applying the offset-preventing agent by means of a rotary or other movable element disposed at a regulated spacing relative to the web or other sheet of material upon which the agent is to be applied, such unit being arranged, when desired, to continue the rotation of the applying element during the period of cessation of operation of the printing units 25 to prevent drying of the agent on the applying element. The unit is also provided with means for discontinuing the operation of the agent applying element, usually and preferably by manual manipulation.

30 The agent applying element is actuated during periods of cessation of the printing and/or other impression machine parts at a speed less, and preferably slightly less, than the normal speed of the element during simultaneous operation 35 with the printing and/or other impressing operations, and suitable means, such as an automatically operatively effective clutch, is provided to substantially instantly accelerate the agent applying element from its lesser idle speed to normal speed.

By such provision of means, many advantages are attained, among them being the facility of the agent applying element to effect operative relation relative to the web or other printed 50 and/or impressed medium substantially instantly upon the starting or re-starting of the printing operations; also, by the continuous movement of the agent applying element during periods of cessation of the printing operation, the agent is maintained in uniform and functional state. It will be appreciated that upon quiescence of the 55 agent applying element, the volatile constituents of the agent evaporate, whereby the resulting residue would render the agent in non-operative state and otherwise "gum up" the agent applying element.

As indicated above, the agent applying unit is also preferably equipped to be shifted to the aforesaid non-coating position, during the stage 60 of threading or re-threading the web or other printed medium through the agent applying unit, and for such other purposes as will be understood by those skilled in the art.

Referring to Figs. 6 and 8, the agent applying 70 element is illustrated in the form of a cylindrical roller 50, the opposite ends, 51a, of its shaft 51, being mounted on or carried in the vertical standards 52 of the frame of the unit, the one shaft end being extended for connection through the

element 50 during the stage of cessation of operation of the printing and/or impression units, such drive being by means of a sprocket gear 54, sprocket chain 55, the latter being connected with a suitable sprocket gear (not shown) secured 5 to a suitable driving shaft.

The driving shaft may be driven by the drive of the printing and/or impression machine proper. If desired, the driving shaft may be driven by an electric or other motor independently of the driving means of the printing and/or impression machine proper.

The agent applying element 50 corresponds to the roll 24, see Fig. 2. Associated with the roll 50 is a web carrying and positioning roll 56 corresponding to the above described associated roll 25. The path of the web 14 toward the agent applying unit is indicated by the applied arrows, and may include idler rollers 58, 59, 60.

Preferably, the web positioning roller 56 is 20 mounted to be shifted relative to the agent applying roller 50, to afford convenience in threading the web through the unit, also for cleansing purposes, etc.; such arrangement may be effected by mounting the web positioning roll 56 on a bracket 25 or like frame, see Figs. 6 and 8, the same comprising the hanger bearing brackets operated by the oppositely disposed arms 61 arranged to be displaced by manual or other operation. As arranged in Fig. 6, the normal operative position of 30 the web positioning roll 56 is effected when the manipulating member 62 is in its position illustrated in this figure. Upon shifting the manual member 62 to its position shown in Fig. 7, the web positioning roll 56 is shifted to spaced relation 35 relative to the agent applying roll 50. As one means of effecting such arrangement, the shifting member 62 may be mounted upon the shaft 63, and cam means provided for operation of the displacing arms 61, as by providing each arm 40 61 with a head 61a functioning with a cam pin 64.

Preferably, and as is embodied in the illustrated unit in Figs. 6 and 9, the web positioning roller 56 is shifted relative to the agent applying roll 50 during stages of stopping of the printing 45 and/or impression units. Preferably, such operation is effected automatically, as will appear more fully hereinafter.

The normal operative drive of the agent applying unit may be had by any suitable means. As 50 illustrated in Figs. 6 and 8, the normal drive is provided by the shaft 65 (corresponding to common drive shaft 38 of printing and/or impression and agent applying units as shown in Fig. 1), on which shaft 65 is keyed or otherwise secured the 55 skew gear 66. The skew gear 66 meshes with the skew gear 67, which latter is loosely mounted about the shaft end 51a of the agent applying roll 50, and connected and disconnected therewith by means of an automatically effective 60 clutch, similar to and if desired a duplicate of the automatically effective clutch 53 between the sprocket gear 54 and the shaft end 51a.

Each automatically effective clutch 53 is of any suitable construction, to provide for the continuation of the drive of the shaft 51 of the agent applying roll 50 by its independent driving means during the period of cessation of the drive of the shaft 65, and to provide substantially instantly upon starting or re-starting of the drive of the 70 shaft 65 for the rotation of the agent applying roll 50 at its normal speed, commensurate with that of the feed of the web 14 through the agent applying unit.

essence a hollow housing 68 having an inner substantially cylindrical face, a therein enclosed ratchet member 69 provided with multiple tapered openings 70. In each opening 70 is enclosed 5 a clutch roller 71, or equivalent, the springs 72 tend to bias the respective clutch rollers 71 toward the tapered, i. e., effectively narrow area of the ratchet openings 70 in the clutch member 69. The clutch members 71 are positioned to 10 engage the inner cylindrical face of the hollow housing 68. Assuming the drive of the shaft 65 to be brought to stop position, the skew gear 66 ceases its rotation, and therewith the skew gear 67, whereby the clutch 53 between the skew 15 gear 67 and the shaft end 51a of the agent applying roll 50 is moved to its clutch open position and substantially simultaneously therewith the clutch 53 between the shaft end 51a and the independently driven sprocket gear 54 is moved 20 to its clutch closing position.

Referring to Fig. 9, assuming the gear 67 to be quiescent, the clutch housing 68 of its clutch is stationary, at which stage the rotation of the 25 sprocket gear 54 continues, actuated by its independent drive, whereby the clutch housing 68 of its clutch 53 is rotated in the direction of the arrow 73, whereby the individual clutch rollers 71 of the independent drive clutch 53 are each moved outwardly in their respective tapered 30 clutch openings, to thereby clutch the member 69 and therewith the shaft end 51a of the agent applying roller 59 to rotate the roller 50 under the independent drive.

Upon resumption of drive of the shaft 65, the 35 skew gear 67 is rotated to its normal speed, greater than that of the speed of rotation of the sprocket gear 54, in which circumstances, the clutch housing 68 of the clutch 53 between the skew gear 67 and the shaft end 51a is rotated in 40 the direction of the arrow 73, see Fig. 9, to thereby close its clutch 53. The speed of the clutch housing 68 secured to the skew gear 67 being greater than the speed of the clutch housing secured to the sprocket gear 54, and the closing of 45 the clutch by the skew gear 67 and the shaft end 51a, causes the shaft end 51a to rotate at a greater speed, thereby causing the clutch 53 between the shaft end 51a and the sprocket gear 54 to be moved to its clutch open position.

50 Appurtenant parts are also indicated in Fig. 6 for the agent applying unit, such as a usual feed roll 76 which extends into the tank 81 containing the agent. Such feed roll is mounted on the shaft of and driven by its gear 82 meshing with 55 its drive gear 83 which is suitably driven, as by securement on the shaft end 51a; I also indicate a "doctor" roll 77, the shaft 84 of which is driven by the gear 85, which may mesh with the gear 82.

60 A convenient type of shift for starting and stopping the respective printing and/or impression units comprises a slide rod 90, see Figs. 6, 7 and 8, which as indicated by the applied arrows and the legends "on" and "off", may be utilized 65 to simultaneously operate the agent applying unit, namely by securing a forked member 91 or equivalent to such rod 90, for receiving in its forked opening a pin 92 of a shifter 93, pivotally mounted at 94 on a suitable bearing, the free end 70 95 of the shifter having a pin 96 for shifting the shift member 62 from its position shown in Fig. 6 to its position shown in Fig. 7, whereby the agent applying unit is shifted from its coating position 75 to its non-coating position automatically upon

shifting the respective printing and/or impression units or stop positions and vice versa.

From the above, it will appear that my process comprises a step of applying to a printed area an agent whereby offsetting is prevented when the 5 printed material is rewound or the otherwise wet ink or other medium of the printed and/or other impressions are brought into contact with an adjacent surface under pressure.

In the claims and in the specification I have 10 employed the expression "offset-preventing agent" to denote an agent such as above specified, or other media, singly or in combination, such agent being applied to the face of the printed paper or the like in fluid status to protect the wet 15 ink (usually containing a drying oil such as linseed oil varnish) without causing blur or other deleterious effect to the inked matter and its outline, and upon evaporation and/or evanescence 20 of the vaporizable ingredient of the agent, the residue forms a non-flowable and/or elastic substantially uniformly distributed coating upon the 25 surface, and permits rewinding of the printed web and/or stacking of the thus treated printed surfaces without offsetting.

Similarly, offsetting is prevented when the 30 printed material in web form is slit and cut into individual printed sheets, and the individual sheets stacked.

In certain classes of printing work, it is desirable 35 to exclude or remove the offset-applying agent from a portion of the face of the web, for example, when it is desired to apply adhesive to such face portion, as for labels, and for other purposes.

To attain such or similar result, the arrangement shown in Fig. 10 may be employed, which arrangement corresponds to that of Fig. 3, with the exception of the addition in Fig. 10 of the collar 30b, or enlarged diameter, adapted to contact with the face of the web to clear the web 40 face of the offset-preventing agent. In a similar manner and in similar functional relationship, a collar or enlarged diameter portion similar to the aforesaid collar 30b, see Fig. 10, may be provided for the agent applying roll 24, to preclude application of the agent upon the face of the web co-extensive with the face of such collar. In the latter form of the device, the agent is non-applied to the face of the web, whereas in the 45 former form of the invention, the agent is removed from the face of the web.

Under certain circumstances, it is desirable to add sheen or enhanced glossing effect upon the unprinted portions of the face of the web or other 50 printed material. To attain such result, I increase the solid content of the agent in proportion to the volatile ingredients, whereby upon evaporation or evanescence of the volatile ingredients, the residual solid portion of the agent 55 is retained on the face of the web.

As will appear from the above, ink or other printing and/or other impression medium when contacted with by the offset-preventing agent is 60 preserved in precise outline. The preservation of 65 the outline of the printed and/or other impression also ensues in the use of the agent for the additive sheen or enhanced glossing effect.

If desired, metallic colors, embossed or non-embossed, may be employed in conjunction with 70 or exclusively of printing in inks or like media. If desired, the printing in color and/or metal may be had in advance of the stage of applying the offset preventing agent.

In the claims, where I use the term "printing" 75

or derivatives thereof, it will be understood that I include all forms of impressions, and where I use the term "ink" or derivatives thereof, I include metallic "colors" as well as ordinary and other approved forms of ink. Also, where I use the term "volatile" in the claims, I include ingredients which escape from the agent by absorption or other form of evanescence, leaving the solid content of the agent as a residue.

10 My invention is of a special advantage in printing or otherwise impressing transparent and other material of non-absorbable character, such as hydrated cellulose, regenerated cellulose, cellulose acetate, glassine paper and the like, also tin foil, aluminum and other metallic foil. In the printing of the above stated non-absorbing types of web or sheet material, as well as for printing of absorbing types of material, slow drying oil inks may be employed.

20 If desired, the coating agent may be applied by utilizing the structure of my invention to the printed surface after the ink and/or other impression has dried, in controlled thickness of coating to thereby regulate the degree of sheen imparted to the web.

25 Whereas I have described my invention by reference to specific forms thereof, it will be understood that many changes and modifications may be made without departing from the spirit of the invention.

30 I claim:

1. The combination of printing means, means for applying an off-set-preventing agent as a substantially continuous film of liquid and means for feeding suitable material firstly through said printing means and thereafter in operative relation with said off-set-preventing agent applying means, said off-set-preventing agent applying means including a roller for applying the stated agent upon the surface of the material inclusive 40 of the printed areas thereof, means for driving said agent applying roller substantially at the surface speed of the material when said roller is in operative relation with the material, and means for effecting removal of said material relative to said agent applying roller.

45 2. The combination of printing means, means for applying an off-set-preventing agent as a substantially continuous film of liquid and means for feeding suitable material firstly through said printing means and thereafter in operative relation with said off-set-preventing agent applying means, said off-set-preventing agent applying means including a roller for applying the stated agent upon the surface of the material, means

for driving the agent applying roller when in operative relation to the material at substantially the surface speed of the material, means for effecting removal of said material relative to said agent applying roller, and means operative upon cessation of said agent applying roller driving means for rotating said agent applying roller at reduced surface speed.

5 3. The combination of a suitable printing means including a printing cylinder disposed opposite its cooperating impression cylinder, means for feeding a web in printing relation with said printing cylinder to impress printed matter upon the upper face of the web, said web feeding means including sets of rolls by which the web is positively fed, means for positively driving said sets of rolls to effect a predetermined surface speed of the web, means for applying a gloss imparting offset preventing agent in the status of continuous flow upon the upper and printed face of the web while the ink of the printed matter is undried, said gloss imparting offset preventing agent applying means including a roll disposed above the upper surface of the web and having its agent applying surface spaced at a clearance from the upper surface of the web, and means for positively driving said agent applying roll at said predetermined surface speed of the web.

10 4. The combination of suitable printing means including a printing cylinder disposed opposite its cooperating impression cylinder, means for feeding a web in printing relation with said printing cylinder to impress printed matter upon the upper face of the web, said web feeding means including sets of rolls by which the web is positively fed, means for positively driving said sets of rolls to effect a predetermined surface speed of the web, means for applying a gloss imparting offset preventing agent in the status of continuous 20 flow upon the upper and printed face of the web while the ink of the printed matter is undried, said gloss imparting offset preventing agent applying means including a roll disposed above the upper surface of the web and having its agent applying surface spaced at a clearance from the upper surface of the web, and means for positively driving said agent applying roll at said predetermined surface speed of the web.
